B. B. RHODEN

COMBINATION GARMENT

Filed March 5, 1923.

Blanche Bell Rhoden Inventor

By Percy H. Moore

Attorney

UNITED STATES PATENT OFFICE.

BLANCHE BELL RHODEN, OF WEST PALM BEACH, FLORIDA.

COMBINATION GARMENT.

Application filed March 5, 1923. Serial No. 622,907.

To all whom it may concern:

Be it known that BLANCHE BELL RHODEN, a citizen of the United States of America, residing at West Palm Beach, in the county 5 of Palm Beach and State of Florida, has invented certain new and useful Improvements in Combination Garments, of which the following is a specification.

This invention relates to "garments" and 10 more particularly to a "lady's undergarment" adapted to be worn next to the body.

It consists of a unitary garment comprising three types of garment as a camisole or bust-confiner, a petticoat or skirt and a 15 chemise or bloomers.

An object of the invention is to provide a unitary garment which obviates the use 20 of any supplemental lingerie, is very comfortable for women to wear and is easily and quickly put on or taken off the wearer's body.

Another object is to provide a garment of this type which is permanently and continuously closed in a horizontal direction 25 thereby eliminating the use of the objectionable body-closure openings and fastening means as hooks and eyes, buttons and buttonholes and snap-fasteners.

In hot climates and warm weather the 30 outline or silhouette of the lower extremities of the wearer can be quite readily observed due to the few and light fabrics worn by women and the transmission of light there thru. An object of this invention is to over- 35 come this objection by obstructing or preventing the passage of light therethru.

Other objects will be observed from the 40 following specification and drawing wherein like numerals designate similar parts.

Figure 1 is a front view of a garment with parts thereof broken away; and

Figure 2 is a rear view of the garment shown in Figure 1.

In Figures 1 and 2 the numeral 24, designates a unitary garment comprising a camisole or bust-confiner 25, a petticoat or skirt 26, and a pair of bloomers 27. The petticoat and camisole are formed of a single 45 unitary piece of material. The camisole or bust confiner is formed by folding the material back upon itself as at 28, to form a substantially wide hem 29, which extends

entirely around the garment from a point above the bust of the wearer to a point below 55 thereof but terminates a substantial distance above the waist line 30, where it is fastened as by stitches 31, to the outer fabric. Extending completely around the top edge of the camisole at a point below the fold 28, 60 is a line of stitches 32, which form a continuous tubular portion for the reception of an elastic web 33. An opening may be provided in this tubular portion. The integral skirt or petticoat extends from the waist- 65 line 30, downward to a point below the crotch and bloomers 27, and has diverging sides 34, and an open end 35, extending from side to side. The petticoat has a single 70 ply upper portion 36, and a double ply lower portion 37, formed by folding the material upon itself to form a substantially wide hem extending from a point below the waist- 75 line 30, but above the crotch and lower portion of the bloomers to a point below the lower ends of the bloomers and completely 80 around the garment in a horizontal direction. The bloomers 27, are attached to the waist-line 30, on the inner side thereof by two horizontally spaced apart and parallel 85 lines of stitches 38, which form a tubular portion 39, adapted to receive an elastic draw string 40. An opening may be provided in this tubular portion. The bloomers are 90 constructed with legs 41 and 42 thereof having a crotch opening 43, extending from the point 44, in front to a point 45, in back and provided with the usual fasteners for closing the same such as buttons and buttonholes. It will be particularly noted that 95 the camisole 25, and skirt 26, are entirely closed in a horizontal direction around the garment.

Having thus described my invention, what I claim is:

A unitary garment of fabric adapted to cover the body in an entirely closed condition circumferentially of the garment with means for contracting the garment about the wearer's body at widely separated points 100 and comprising an upper garment and a plurality of superimposed lower garments, said upper garment and the outer of said superimposed lower garments being integrally 105 connected by a waistline portion, said upper garment being of double ply construction

extending from a point above to a point below the wearer's chest and above said waist line portion, the inner of said superimposed lower garments being connected to said 5 waistline portion and the outer of said superimposed lower garments being of double ply construction with the inner ply extending

from the lower part thereof to a point above the wearer's crotch and terminating below said waistline portion and being independent of said inner lower garment. 10

In testimony whereof I affix my signature.

BLANCHE BELL RHODEN
